ELECTRIC SYSTEM FOR OPERATING TRACK SWITCHES

Frank H. Richterkessing, Louisville, Ky.

Application June 30, 1930, Serial No. 464,972

15 Claims. (Cl. 246—227)

My invention relates to an electric system for operating track switches, and is particularly adapted to be controlled by an operator on an electric car.

5 One of the objects of my invention is to supply switch operating current to the system for a predetermined time regardless the position of the car after having once set the system in operation.

Another object of my invention is to provide 10 means for automatically selecting the position of the track switch from the car through the medium of the motor controller, when thrown to either "power on" or "power off."

Another object of my invention is to prevent 15 the track switch mechanism from being operated to the wrong position by a car after having been initially operated to the correct position.

Another object of my invention is to provide a 20 system which is operable when trolley contactors are engaged successively in one direction only, and which is further arranged so that a car moving in either direction will restore the system to normal after the last of the succession of contactors is engaged.

25 A still further object is to reduce the magnitude of the arcs broken at the trolley contactors to a practical minimum.

A still further object of my invention is to 30 provide a system of signal indications for indicating the exact condition and position of the track switch mechanism.

A still further object of my invention is to provide means whereby the first car, after having 35 initially operated the track switch to the desired position, will automatically prevent a following car from subsequently operating the switch until after the first car has passed a predetermined point. Other objects will disclose themselves as the disclosure of my invention is made herein.

40 My invention resides in a new and novel construction, the combination and relation of the various parts and circuits herein described and disclosed in the drawing accompanying this specification; in which:

45 Figure 1 is a diagram illustrating the circuits of an electric car that are taken into account in the operation of my invention.

Fig. 2 is a schematic drawing of my invention 50 showing the relations of the various parts and circuits when the system is in a normal condition, that is, prior to an operation for positioning the track switch. The switch tongue, however, may be shown in either of its positions.

55 As hereinbefore mentioned, it is the object of

my invention to provide a system by means of which a track switch is automatically and electrically operated to its straight ahead or curved position, dependent upon the car operator setting the motor controller in the "power on" or "power off" position. The system utilizes the principle that when the controller is set to the "power off" position, no current flows through the motors, and when the controller is set to the "power on" position, a heavy current flows through the 10 motors. The flow and non-flow of current is made use of in the operation of the system for selecting the position of the switch tongue. There are other currents flowing through other electrical circuits of the car, which circuits are not under 15 the control of the motor controller, and these must be taken into consideration in designing the system. These circuits are referred to as the auxiliary car circuits and are known as the heat, 20 light and air compressor circuits.

In Fig. 1, the letter W represents a trolley wheel or current collector, and the letter T represents a trolley pole by which the current collector is mounted upon the car. H indicates the 25 heaters, L the lights, J the air compressor, and these, when in operation, together with possibly others, may total a considerable amount of current. The motors for moving the car are indicated by M, and, the controller by which the 30 current to the motors is controlled, is indicated by the letter C. All the circuits for the car are connected to the ground G.

In the preferred embodiment of my invention, which is shown in a normal condition in Fig. 2, 35 P represents a trolley pan or contactor positioned adjacent the trolley wire 1, and is so arranged that, when the current collector W comes into engagement with its contact members 2 and 3, it will pass out of contact engagement with the 40 trolley conductor 1 and into contact engagement with the contact members of the trolley contactor P. The trolley contactor P comprises two laterally-spaced, parallel contact-members 2 and 3, which contact-members are normally insulated 45 from each other and the trolley conductor 1, and are so positioned that the current collector will bridge the two when passing thereover.

I also employ a track switch mechanism TM 50 connected to the track switch tongue by an operating plunger PL. The electrically operated mechanism for the tongue comprises two solenoids N and R, one terminal of each solenoid being connected to the ground G through a common conductor 21. Reciprocally operating with- 55

in the solenoids in the plunger PL, which plunger is drawn inwardly when the solenoid R is energized, and drawn outwardly when the solenoid N is energized, and, being connected to the 5 switch tongue, moves the tongue to one or the other of its positions. The plunger PL also operates a circuit controller K through a connecting rod O. The circuit controller K is provided with a common armature A8 operating between 10 two contacts 45 and 47, and the armature A8 is connected to the ground G through wire 48.

I also employ an electrically operated switch RD, which I will term a selective switch as its function is to place one or other of the solenoids 15 in an operating circuit, when the current collector engages the trolley contactor P. The switch RD is provided with an operating coil KL and has one coil terminal connected to the trolley wire 1 through wire 18, knife switch blade 20 9, and wire 7, and its other terminal connected to contact member 2 of the trolley contactor P through wire 6, knife switch blade 5 and wire 4. The coil KL preferably consists of a few turns of 25 heavy wire, as it must withstand a very heavy current flowing therethrough. It must also have its ampere turns so proportioned that it will operate to raise its switch arm A5, when the controller C is in the "power on" position and the current collector W in contact engagement 30 with the trolley contactor P, and which will not affect the armature A5 when the controller is in the "power off" position. Further, the ampere turns must be so regulated that the current flowing through the auxiliary circuits, which will 35 also flows through the operating coil KL, will not affect the armature A5, when the current collector W engages the trolley contactor P with power off. Contact member 2 is electrically connected to the trolley wire 1 at all times via coil 40 KL, and, when the current collector engages the trolley contactor P with power on, current flows from the trolley wire to the contact member 2, through the current collector W, trolley pole T, controller C, motor M to the ground G, and, in- 45 cident to this operation, contact member 3 is electrically connected to the trolley wire 1, through the current collector W. The selective switch RD is also provided with two contacts 18 and 22, and a switch arm A5 normally in contact 50 engagement with back contact 18. Therefore, the selector switch the letters RD is normally set for operating solenoid R, and remains so set, when the collector engages the pan with "power off." When the collector engages the contactor 55 P with "power on," armature A5 engages contact 22, thereby connecting solenoid N for operation. The selector switch RD is also provided with a holding coil D, which coil is connected in series 60 with solenoid N, for retaining armature A5 raised until the operating current flowing to solenoid N is interrupted.

The electrically operated switch RS is provided with an operating coil A having one of its terminals connected to the contact member 3 of 65 trolley contactor P through wires 25, 27 and switch blade 26, and its other coil terminal connected to the ground G, through wire 28, the resistance unit R1, wire 16, coil S, wire 17, armature A5, back contact 18, wire 19, solenoid R, 70 wire 20, wire 21. It is not necessary that the operating current for coil A be taken to the ground through the track switch operating solenoid, as it may be taken directly to the ground G without interfering with the functions of the 75 various parts as required. The resistance of coil

A is sufficiently high so that only a slight arc takes place, when the current collector W disengages the trolley contactor P. Relay RS is also provided with an armature A1, which armature is normally out of contact engagement with its front contact 15. The relay RS is also provided with a holding coil S, which coil is connected in series with the switch operating circuit for retaining armature A1 raised until the flow of switch operating current is interrupted. 10

The normally-energized retarded-release magnetic-blowout relay RB is provided with an operating coil B having one of its coil terminals connected through wire 34, contact 35 of the normally closed trolley contactor Y, contact strip 15 3B of normally closed trolley contactor Y, wire 36 to the trolley conductor 1, and its other coil terminal connected to armature A2 of relay RL by wire 33. Relay RB is also provided with an armature A3, which armature is normally in contact engagement with its front contact 13. The armature A3 and front contact 13 operate within a magnetic blowout, the construction of which is well known to those skilled in the art. This is symbolically represented by the characters MB. 25 The retarded-release time-element factor of relay RB is symbolically represented by BT, and this may be brought about by various well known constructed principles of the art, namely, a brass or copper sleeve placed about the core of the 30 operating coil B or by dash pot arrangement connected to the armature A3.

The locking relay RL is provided with an operating coil L and has one of its coil terminals connected to a resistor R1, through wire 29, and its other coil terminal connected to contact strip 5B of trolley contactor U through wire 30, and front contact 32 through wire 31. The relay RL is also provided with an armature A2, which armature is normally in contact engagement with 40 its front contact 32.

The light controlling relay RQ is provided with an operating coil Q and an armature A4. The armature A4 and one coil terminal of its operating coil Q is connected to the trolley conductor 45 1 through resistance unit R2, wire 12, wire 11, wire 10, knife switch blade 9 and wire 7. The other coil terminal of the operating coil Q is connected to a common connection 49 of the indicating lights GL and YL through wire 39. The 50 normally disengaged back contact 41 of relay RQ is connected to the RL1 light indication, through wire 42.

The indicating lights GL, YL and RL1 are disposed within a suitable housing, and are placed 55 behind colored lenses to give the desired indications.

The uni-directional trolley contactor Z is placed in advance of the switch operating contactor P, and operates in conjunction with directional relays RE and RF. The uni-directional trolley contactor Z is provided with two contact members 3A and 5A. These contact strips are constructed and arranged so that the current collector W successively connects them to the trolley 65 conductor 1 upon passing through the contactor. Relays RE and RF selectively operate according to the direction of travel of the current collector W, and require successive contact engagement of contact strips 3A and 5A. Relay RE is provided 70 with an operating coil E and has one of its coil terminals connected to the ground G through the resistance unit R3 and wire 55, and its other coil terminal connected to strip 5A of trolley contactor Z through wire 54 and to one terminal of 75

coil F through wire 53. The relay RE is also equipped with an armature A6 and a normally disengaged front contact 51. The armature A6 is connected to the other contact strip 3A through wire 49. Relay RF is provided with an operating coil F and has one of its coil terminals connected as aforesaid, and its other terminal connected to front contact 51 of relay RE through wire 52. The relay RF is also equipped with an armature A7 and a normally disengaged front contact 56. The front contact 56 is connected to the trolley contactor U through wires 60 and 61. The armature A7 is connected to the trolley conductor I, through wires 50, 10, knife switch blade 9 and wire 7. A more complete description of the circuits and disposition of these parts is presented hereinafter.

The three pole double throw switch SW is so arranged and connected that when it is in one position the switch controlling relays are in circuit with the switch operating contactor P, and when it is thrown to the other position the relays are disconnected from the trolley contactor P, and the contact member 2 of the trolley contactor P is directly connected to the trolley conductor I, through wires 7, 8, knife switch blade 5 and wire 4.

As the current collector W approaches the switch operating contactor P in the direction of the arrow AR, it first engages contact strip 3A of trolley contactor Z. As this contact engagement is completed no operation of the selective relay RF can result as its operating circuit is open at the armature A6 of relay RE. As the wheel continues its course of travel, and engages contact strip 5A of trolley contactor Z, a circuit is completed through the operating coil E of relay RE. This operation of relay RE will not affect the operation of the switch operating circuits as a successive operation of relays RE and RF must occur.

If the current collector initially engages the switch operating contactor P with power off, the operating coil KL of the selective switch RD is not sufficiently energized to raise its armature A5, and the normal selection of armature A5 is retained. As the current collector comes into contact engagement with the contact strip 3 of trolley contactor P, a circuit is completed through the normally deenergized operating coil A of relay RS. This circuit is completed from the contact strip 3, through wire 25, knife switch blade 26, wire 27, operating coil A of relay RS, wire 28, resistance unit R1, wire 16, low resistance coil S, wire 17, armature A5 of relay RD, back contact 18 of relay RD, wire 19, switch operating solenoid R, wire 20, wire 21, to the ground G. As the armature A1 of relay RS is brought into contact engagement with its normally disengaged front contact 15 a circuit is completed to the switch operating solenoid R of the track switch TM, from the trolley conductor I, through wire 7, knife switch blade 9, wire 10, wire 11, armature A3 of relay RB, normally engaged front contact 13 of relay RB, wire 14, armature A1 of relay RS, front contact 15 of relay RS, wire 16, holding coil S of relay RS, wire 17, armature A5 of relay RD, back contact 18 of relay RD, wire 19, solenoid R, through wire 20, wire 21 to the ground G.

Instant to this operation, the normally energized relay RL instantly releases its armature A2 through the application of a shunt circuit effected by the engagement of contact 15 and armature A1 of relay RS. The releasing of armature A2 of relay RL, opens the circuit of the operating coil B of relay RB, since the relays RB and RL have their operating coils B and L normally connected in series. This normal circuit is completed from the trolley conductor I, through wire 36, contact strip 3B of trolley contactor Y, contact 35 of trolley contactor Y, wire 34, coil B of relay RB, wire 33, armature A2 of relay RL, normally engaged front contact 32 of relay RL, wire 31, operating coil L of relay RL, wire 29, resistance unit R1, wire 16, low resistance coil S, wire 17, armature A5 of relay RD, back contact 18 of relay RD, wire 19, solenoid R, wire 20, wire 21 to the ground G. As hereinbefore mentioned, the releasing of armature A2 by relay RL, opens the operating circuit of coil B of relay RB, but the armature A3 of relay RB is retarded in its release, as heretofore described. After a predetermined time armature A3 disengages front contact 13 of relay RB within the magnetic blowout MB, and the current flowing to the switch operating solenoid R is interrupted. Relays RB and RL remain in their deenergized positions irrespective of the length of contact engagement of the current collector W with the contact member 3 of the trolley contactor P, and until the current collector continues its course of travel and comes into contact engagement with the contact strip 5B of the trolley contactor U, wherein a circuit is established for re-energizing operating coil L of relay RL. This circuit is completed from the trolley conductor I, through the current collector W, contact strips 5B of trolley contactor U, wire 30, solenoid L of relay RL, wire 29, resistance unit R1, wire 16, holding coil S of relay RS, wire 17, armature A5 of relay RD, contact 18 of relay RD, wire 19, solenoid R, wire 20, wire 21 to the ground G. The energization of operating coil L of relay RL raises armature A2 into contact engagement with front contact 32. However, the operating coil B of relay RB is not reenergized until after the current collector W disengages contact strip 5B of trolley contactor U, wherein the normally energized circuits for relays RB and RL are re-established. In the event of multiple car-train operation, trolley contactor U is replaced by two trolley contactors X and XI, as shown in dotted lines. The purpose of this arrangement is to assure the switch operating circuit being held open until after the cars have cleared the switch point. The function of the normally closed trolley contactor Y, located between the switch operating contactor P and the unlocking trolley contactor U, is to assure the opening of the circuit for coils B and L, of relays RB and RL, before the car enters the switch point. This is a very desirable feature, especially when one or more cars follow closely over the switch point, since without the use of this trolley contactor, it would be possible to have a car enter the switch point without the circuits being properly electrically locked.

It is often desirable to permit cars to trail through the switch point in the opposite direction, and, with the ordinary apparatus heretofore employed, the circuits are left open. The directional sensitive trolley contactor Z is incorporated in the system so that the passage of the current collector in one direction will not affect the relay L of the switch operating control, but the passage of the current collector W in the opposite direction will restore the system to a normal operating condition. It can be seen that the current collector W moving in the direction opposite to that indicated by the arrow AR, first engages trolley contactor U, and energizes re-

lay RL, for restoring the system to a normal condition. After this, the collector W engages the auxiliary locking contactor Y, and opens the circuit of relays RL and RB, for opening the switch operating circuit. Therefore, when the switch operating contactor P is subsequently engaged, the switch solenoids are not energized, as their circuits are open. However, when the current collector W engages the trolley contactor Z, the circuits are restored to their normal operative conditions. This operation is affected by the successive contact engagement of contact strip 5A and contact strip 3A.

The light indications of the system are so arranged that, when the switch is thrown to one position and electrically locked, a yellow light YL indicates, and, when the switch is thrown to the opposite position and electrically locked, a green light GL indicates, and if the switch is operated to a mid-position, which would be a dangerous condition, neither the green or yellow lights indicates and a red light RL4 is displayed to warn of this dangerous condition. This is brought about through the application of the relay RQ, used in conjunction with the switch circuit controller operated by the movement of the switch plunger.

There are, of course, modifications and arrangements of parts which may be made from that shown in the above disclosure and which will still fall within the scope of my invention.

I claim:

1. In a track-switch operating system comprising, in combination, a track-switch; a solenoid for operating the said track-switch; a trolley-conductor; a normally-open circuit including the trolley-conductor and solenoid; a vehicle-actuated device normally electrically-connected to the said trolley-conductor; vehicle-controlled means for closing the said normally-open circuit; and vehicle-responsive means, controlled by electrically-disconnecting the said device from the said trolley-conductor, for rendering the said circuit inoperative by the said vehicle-controlled means.

2. In a track-switch operating system comprising, in combination, a track-switch; actuating solenoids for operating the said track-switch selectively; a branched operating circuit for energizing the said solenoids selectively to provide for the aforesaid selective operation of the track-switch; a circuit-changer for connecting selectively the branches of the said operating circuit to their corresponding solenoids to provide for the aforesaid selective energization thereof; a normally-open switch included in the said operating circuit; means for closing the said normally-open switch; means for retaining the said normally-open switch closed comprising an operating coil of relatively low resistance included in the said operating circuit; a normally-closed switch included in the said operating circuit; a normally-energized circuit including an operating coil and normally-closed contact of a stick relay, and an operating coil of the said normally-closed switch; and means, operating in response to the closing of the said normally-open switch, for de-energizing the said normally-energized circuit to open the normally-closed contact of the said stick relay; and means for reclosing the contacts of the said stick relay to re-energize the said relay circuit.

3. A track-switch operating system comprising, in combination, a track-switch; electro-magnetic operating means for the said track-switch; an operating circuit therefor; a switch-operating contactor; normally-de-energized relay-means,

operatively connected to the said switch-operating contactor and energized in response to an actuation thereof, for closing the said operating circuit; a normally-energized relay-means for opening directly the said operating circuit; means, operating in response to the closing of the said operating circuit, for de-energizing the said normally-energized relay-means, to render thereby inoperative the said electro-magnetic operating means to subsequent energizations of the said normally-de-energized relay-means; a restoring contactor; and means, operatively connected to the said restoring contactor and operating in response to an actuation thereof, for re-energizing the said normally-energized relay-means.

4. In a track-switch operating system comprising, in combination, a track-switch; an actuating solenoid therefor; a trolley-conductor; a normally-open switch-operating circuit including the said trolley-conductor and actuating solenoid; a switch controlling the said operating circuit; vehicle-responsive means for closing the switch controlling the said circuit, thereby to energize the said solenoid; a protective device for rendering the said operating circuit inoperative to energize the said solenoid; vehicle-responsive means adapted to be operated successively by a vehicle moving in one or the opposite direction, for operating the said protective device; means operatively associated with the first and last of the said vehicle-responsive devices, for restoring the said protective device to normal to render thereby operative the said operating circuit, when either of the said first and last devices are operated by a vehicle moving in the said one direction; and means operatively associated with the said last of the devices, for restoring the said protective device to normal to render thereby operative the said operating circuit, when the said last device is operated by a vehicle moving in the said opposite direction.

5. In a track-switch operating system, the combination of an electrically-operated track-switch; an operating circuit therefor; a normally-energized relay for directly controlling the said operating circuit; a second normally-energized relay for controlling the first mentioned relay; a normally-de-energized relay for closing the said operating circuit; means for energizing the last mentioned relay; means, responsive to the closing of the said operating circuit for de-energizing the said second relay, thereby to de-energize the first mentioned relay means; and means for re-energizing the said second relay means.

6. An automatic locking system for electrically-operated track-switches comprising, a track-switch; electro-magnetic means for operating the said track-switch; a trolley-wire; a plurality of vehicle current-collectors at a distance from each other and co-operative with the said trolley-wire; a switch-operating contactor and a restoring contactor, each positioned adjacent the trolley-wire at a distance from each other and actuatable by the said current collectors; a normally-open switch-operating circuit including the said electro-magnetic means and the trolley wire; a normally-energized main relay having a normally-closed contact thereof included in the said operating circuit; a normally-energized locking-relay controlling the energization of the normally-energized main-relay; a control-relay, operating in response to an actuation of the said switch-operating contactor, for closing the said switch-operating circuit; means, operating in response to the

aforesaid operation of the said control relay, for de-energizing the said normally-energized locking-relay, thereby to de-energize the said normally-energized main-relay for rendering inoperative 5 the said electro-magnetic means as soon as the said normally-closed contact of the normally-energized main relay opens in response to the operation of the last mentioned means; and means, operating in response to an actuation of the said 10 restoring contactor, for re-energizing the aforesaid normally-energized locking relay; the said electro-magnetic means being thus rendered inoperative until the first of said current collectors, after having actuated the said switch-operating 15 contactor, actuates the said restoring contactor.

7. In an automatic locking system of the character set forth in claim 6 comprising, an auxiliary locking-contactor positioned adjacent the said trolley wire, at a point between the aforesaid 20 switch-operating and restoring contactors, and actuatable by the aforesaid current collectors; and means, operating in response to an actuation of the said auxiliary locking-contactor, when the said first of the current-collectors actuates the said restoring contactor after a subsequent current-collector has actuated the said switch-operating contactor, for de-energizing the aforesaid normally-energized locking-relay; the said electro-magnetic means being thus rendered 25 30 further inoperative, as aforesaid, until the said subsequent current collector, after having actuated the said auxiliary locking-contactor, actuates the said restoring contactor.

8. In a track-switch operating system comprising, in combination, a track-switch; a solenoid for operating the said track-switch; an operating circuit for the said solenoid; a normally-open relay-switch and a normally-closed relay-switch electrically connected in series and included in 35 40 the said operating circuit; a normally-de-energized operating-coil, which, when energized, closes the said normally-open relay-switch, and a normally-energized relay-coil, which, when de-energized, opens the said normally-closed switch; means for energizing the said normally de-energized relay-coil; and means, operating in response to the aforesaid energization of the said normally-de-energized relay-coil, for de-energizing the said 45 50 normally-energized relay-coil, thereby to open the said normally-closed relay-switch and to render the said circuit ineffective to subsequent closings of the said normally-open relay-switch.

9. An automatic locking-system for electrically-operated track-switches comprising, a track-switch; electro-magnetic means for operating the said track-switch; a trolley-wire; a plurality of vehicle current-collectors spaced a distance from each other and cooperative with the said trolley-wire; a switch-operating contactor 55 60 and a restoring contactor, each positioned adjacent the trolley-wire at a distance from each other and actuatable by the said current collectors; an operating circuit including the said electro-magnetic means; a first normally-energized relay having a normally-closed contact thereof included in the said operating circuit; a second normally-energized relay controlling the energization of the first relay; a third normally-de-energized relay having a normally-open contact 65 70 included in the said operating circuit; a first control-circuit including an operating coil of the third relay and the said switch-operating contactor, for energizing the said third relay to close the normally-open switch thereof, when a collector actuates the said operating-contactor; a sec-

ond control-circuit including the operating coils of the first and second relays and a normally-closed contact of the second relay; means, operating in response to the closing of the normally-open switch of the third relay, for de-energizing 5 the said second relay, thereby to open the said second control-circuit; a third control-circuit including the operating coil of the said second relay and the said restoring contactor, for re-energizing the said second relay, when a collector 10 actuates the said restoring contactor, thereby to re-close the said second control-circuit, whereby the said electro-magnetic means is rendered inoperative until the first of said collectors, after having actuated the said switch-operating contactor, actuates the said restoring contactor. 15

10. In a track-switch operating system comprising, in combination, a track-switch; electro-magnetic means for operating the said track-switch; a trolley-wire; a switch-operating contactor and a restoring-contactor, positioned adjacent the said trolley-wire; a normally-open circuit including the said electro-magnetic means and the trolley-wire; a normally-open switch and a normally-closed switch electrically connected in 20 25 series and included in the said normally-open circuit; an operating-coil for each of the said switches; a lock-control relay; a normally-closed circuit including an operating-coil and normally-closed contact of the said lock-control relay and 30 an operating coil of the said normally-closed switch; a control-circuit including the operating-coil of the said normally-open switch and the said switch-operating contactor; and a restoring circuit including the coil of the said lock-control 35 relay and the said restoring contactor.

11. A track-switch operating system comprising, in combination, a track-switch; actuating solenoids for operating the said track-switch selectively; an operating circuit having branches 40 for energizing each solenoid selectively; a circuit-changer for connecting selectively the said solenoids in the corresponding branches of the said operating circuit to provide for the aforesaid selective energization thereof; a normally-energized relay having a normally-closed contact thereof included in the said operating circuit for controlling directly the energization of the solenoid connected in either branch of the said operating circuit; a normally-open switch for closing the said operating circuit to energize the solenoid connected in either branch thereof; means for closing the said normally-open switch; a relay coil included in the said operating circuit, and energized by the flow of solenoid current in the said operating circuit, for holding the normally open switch in closed condition; and means, operating in response to the closing of the said normally open switch for de-energizing the said normally energized relay, thereby to open 50 55 60 65 70 the said operating circuit for de-energizing the solenoid selectively connected in either branch of the said operating circuit.

12. A track-switch operating system comprising, in combination, a track-switch; electro-magnetic means for operating the said track-switch; a normally-open circuit including the said electro-magnetic means; a normally de-energized relay having a normally-open switch thereof included in the said circuit; a first normally-energized relay having a normally-closed switch thereof included in the said circuit; means for energizing the said normally de-energized relay to close the said normally-open switch, and thereby to close the said normally-open circuit; 75

a second normally-energized relay, which, when de-energized, de-energizes the said first relay; and means, operating in response to the closing of the said normally-open circuit, for de-energizing the said second relay, thereby to de-energize the said first relay.

13. A track-switch operating system comprising, in combination, a track-switch; electro-magnetic means for operating the said track-switch; a normally-open circuit including the said electro-magnetic means; a normally-open switch for closing the said circuit; a first normally energized relay having a normally-closed switch thereof included in the said circuit; a second normally-energized relay; a normally-closed circuit including the operating coils of the said first and second relays and a normally-closed switch of the said second relay; and means, operating in response to the closing of the said normally-open switch, for de-energizing the said first and second relays, thereby to open the said normally-open circuit including the normally-closed switch of the first relay, and to open the normally-closed circuit including the normally-closed switch of the second relay.

14. A track-switch operating system comprising, in combination, a track-switch; electro-magnetic means for operating said track-switch; a normally-open circuit including the said electro-magnetic means; a normally-open switch for closing the said circuit; means for closing the said normally-open switch; a first normally-

energized relay having a normally-closed switch thereof included in the said circuit; a second normally-energized relay, which, when de-energized, de-energizes said first relay; and means, operating in response to the closing of the said normally-open switch, for de-energizing the said second relay.

15. A track-switch operating system comprising, in combination, a track-switch; electro-magnetic means for operating the said track-switch; a normally-open circuit including the said electro-magnetic means; a normally de-energized relay having a normally-open switch thereof included in the said circuit; a first normally-energized relay having a normally-closed switch thereof included in the said circuit; means for energizing the said normally de-energized relay to close the said normally-open switch, and thereby to close the said normally-open circuit; a second normally-energized relay, which, when de-energized, de-energizes the said first relay; means, operating in response to the energization of the said normally de-energized relay, for de-energizing the said second relay, thereby to de-energize the said first relay; and timing means, operatively associated with the normally-closed switch of the said first relay, for delaying the opening of the said normally-closed switch for a predetermined period of time after the de-energization of the said first relay.

FRANK H. RICHTERKESSING.
